ACCORDION STRAP ADJUSTING DEVICE

John M. Bolster, Minneapolis, Minn., assignor to
Edward Traficante, Minneapolis, Minn.

Application September 4, 1937, Serial No. 162,472

1 Claim. (Cl. 84—376)

My invention relates to accordions and particularly to adjusting devices for the wrist-engaging straps thereof.

Proper and comfortable operation of an accordion requires that the strap which engages the left hand of the operator be adjustable to enable obtaining a degree of slack therein which permits proper operation of the accordion bellows and easy fingering of the keys controlled by the left hand. It is, of course, highly desirable that the strap-adjusting means be quickly and easily manipulatable to obtain a desired adjustment and that the adjusting means does not constitute an obstruction or impair the appearance of the accordion. The usual type of strap-adjusting means employed on accordions constitutes an obstruction of not particularly pleasing appearance and which may be relatively easily entangled with portions of a musician's costume or other articles.

A general object of my invention is to provide an accordion strap-adjusting device which may be almost entirely concealed within the structure of an accordion, which will not detract from the appearance of an accordion, which cannot constitute an obstruction, and which may be unusually easily manipulated.

Another object is to provide an accordion strap-adjusting device enabling concealment of the end of the strap connected therewith and associated construction whereby the remaining end of the strap may be concealed to harmonize with the first mentioned end.

Still another object is to provide an accordion strap-adjusting device of such construction that only a segment of a rotary control element thereof is visible from the exterior of the accordion.

A further object is to provide such a strap-adjusting device of simple, compact, rugged, effective and inexpensive construction.

These and other objects and advantages of the invention will more fully appear from the following description, made in connection with the accompanying drawing, wherein like reference characters refer to the same or similar parts throughout the several views, and in which—

Fig. 1 is a top view of an accordion having an embodiment of my invention incorporated therein;

Fig. 2 is a partial rear view partially broken away to show parts embodying my invention;

Fig. 3 is a section taken along the line 3—3 of Fig. 2, as indicated by the arrows, and

Fig. 4 is a section taken along the line 4—4 of Fig. 2, as indicated by the arrows.

Referring to the drawing, an embodiment of my invention is shown associated with an accordion A which includes a keyboard 5 and a pair of boxes 6 and 7 having bellows 8 therebetween and attached to the respective boxes 6 and 7 in the usual manner. The lower (as in Figs. 1, 2 and 3) side of the box 7 includes a removable panel 9, which is normally secured to the box 7.

As usual in accordion construction a strap 10 is provided extending longitudinally of the lower side of the accordion, this strap being adjustable as to the amount of slack therein by suitable means.

The right hand end of the removable panel 9 is notched at 9a to provide an opening through which the right hand end of the strap 10 extends into the interior of the box 7. I provide suitable means for securing the right hand end of the strap to the inner side of the panel 9. This means may consist of a metal plate 11 and screws 11a extending through the metal plate 11, the strap 10 and into the material forming the panel 9.

The remaining or left hand end of the panel 9 is provided with a notch 9b through which the remaining or left hand end of the strap 10 projects into the interior of the box 7. An elongated externally screw threaded element 12 is attached to the left hand end of the strap 10 to project therebeyond as shown in Figs. 2 and 3. An element 12a of U-shaped cross section is joined with the inner end of the elongated element 12 and receives the end of the strap 10.

The U-shaped element 12a is secured to the strap 10 by suitable means such as the rivets 13. Beyond the end of the strap 13 a bracket 14 is secured to the inner side of the left hand (as viewed in Fig. 2) wall 7a of the box 7. The bracket 14 has an inwardly directed portion 14a which is provided with a central aperture through which the elongated element 12 projects. A moderate distance beyond the bracket 14 a second bracket 15 is secured to the inner side of the left hand wall of the box 7. The second bracket 15 is provided with an inwardly projecting portion 15a which has an aperture aligned with the aperture of the first bracket 14 and through which the elongated element 12 extends.

A centrally apertured and internally screw threaded operating element 16 preferably of circular peripheral shape is screw threadedly mounted on the elongated element 12 between 55

the portions 14a and 15a of the respective brackets 14 and 15. The rotary operating element 16 is provided with journals 16a on the respective sides thereof, these journals being rotatably disposed in the apertures of the respective brackets 14 and 15. The journal 16a at the lower side of the element 16 is shouldered at its inner portion as at 16b to form a surface for bearing against the bracket 14. Obviously rotation of the rotary element 16 will cause movement of the elongated element 12 axially thereof and, hence, will reduce or increase slack in the strap 10.

The above described parts are so arranged that the rotary control element 16 may be manipulated from a point exterior to the box 7. For this purpose the left hand wall 7a of the box 7 is provided with a slot 17 and the rotary element 16 is of such diameter as to project in a portion thereof through the slot 17 to expose a segment of the rotary element 16 exteriorly of the box 7.

It is to be noted that the strap-adjusting device described above is so arranged that all of the same except for a segmental portion of the rotary control element 16 is contained and concealed within the box 7. It is to be noted that the device includes no portions of such a nature as to impair the external appearance of the accordian or constitute an obstruction which may become entangled with a user's clothing or other articles. It is also to be noted that the right hand end of the strap 10, as viewed in Fig. 2, is anchored by means contained and concealed within the box 7, so as to be in accord with the concealed arrangement of the adjusting device at the left hand end of the box 7. Furthermore, when the panel 9 is removed for obtaining access to the interior of the accordian, the panel 9 may be swung outwardly and to the left with the strap 10 moving therewith so as to enable completely unobstructed access to the interior of the accordian. In this connection, it is to be appreciated that the usual means for attaching a strap, such as the strap 10 to an accordian, are mount-

ed on the exterior of the box 7 in such manner that removal of the panel 9 does not swing the strap out of a position wherein it will partially obstruct access to the interior of the accordian.

It is apparent that I have invented a novel, effective, compact, simple, easily operated and almost entirely concealed form of adjusting and attaching means for an accordian strap.

It will, of course, be understood that various changes may be made in the form, details, arrangement and proportions of the various parts without departing from the scope of my invention, which, generally stated, consists in the matter shown and described and set forth in the appended claim.

What is claimed is:

In an accordian including a box at one end thereof and a wrist-engaging strap extending longitudinally of the outer side of said box, one end of said strap being secured to one end of said outer side, the remaining end of said outer side having an opening therethrough through which the remaining end of said strap projects into the interior of said box, a pair of spaced elements mounted in said box and having aligned apertures through the respective ones thereof aligned with said remaining end of the strap, an elongated externally screw-threaded element secured at one of its ends to said remaining end of the strap and extending therefrom through the apertured portions of said spaced elements, and a centrally apertured and internally screw-threaded rotatable element screw-threadedly mounted on said elongated element between said spaced elements, said box having an opening therein aligned with the space between said spaced elements and part of the marginal portion of said rotary element being projected through said opening to present a portion of the periphery of said rotary element exteriorly of said box to enable convenient manipulation of said rotary element for varying the slack in said strap.

JOHN M. BOLSTER. 45
